(57) **CLAIM**

We claim the ornamental design for footwear, as shown and described.

DESCRIPTION

FIG. 1 is a photographic front perspective view of footwear, showing our new design;

FIG. 2 is a left side view thereof;

FIG. 3 is a right side view thereof;

FIG. 4 is a front view thereof;

FIG. 5 is a rear view thereof; and

FIG. 6 is a top view thereof.

FIG. 7 is a photographic front perspective view of the footwear shown in FIGS. 1-6 in condition of use with a broken line sole;

FIG. 8 is a left side view thereof;

FIG. 9 is a right side view thereof;

FIG. 10 is a front view thereof;

FIG. 11 is a rear view thereof; and,

FIG. 12 is a top view thereof.

The broken lines are provided for environmental purposes only and form no part of the claimed design.

1 Claim, 12 Drawing Sheets
